(57) CLAIM

The ornamental design for soccer ball bank, as shown and described.

DESCRIPTION

FIG. 1 is a perspective view of a soccer ball bank showing my new design;

FIG. 2 is a bottom plan view thereof;

FIG. 3 is a left side elevational view thereof, the right side being a mirror image; and,

FIG. 4 is a top plan view thereof.

All surfaces not shown form no part of the claimed design.
